UNITED STATES PATENT OFFICE.

THOMAS SINGLETON, JR., OF NEW BEDFORD, MASSACHUSETTS, ASSIGNOR
TO THE MOUNT WASHINGTON GLASS COMPANY, OF SAME PLACE.

DESIGN FOR THE ORNAMENTATION OF GLASSWARE.

SPECIFICATION forming part of Design No. 21,173, dated November 17, 1891.

Application filed July 9, 1891. Serial No. 398,973. Term of patent 7 years.

To all whom it may concern:

Be it known that I, THOMAS SINGLETON, JR., of New Bedford, in the county of Bristol and State of Massachusetts, have invented and produced a new and original Design for the Ornamentation of Glassware, of which the following is a specification, reference being had to the accompanying drawings, forming part hereof, in which—

10 Figure 1 is a side elevation of a dish containing my design. Fig. 2 shows the design laid out.

15 My new design herein shown and described is applicable to both cut and pressed glass-
ware; and it consists in the combination of figures hereinafter described.

20 A A', &c., are a series of fan figures; B B', &c., a series of ornamented diamond-shaped figures; D D', &c., a series of diamond-shaped figures, the folds of each fan figure extending from a common center *a*, which is at the point *d* of each figure D D', &c., quarter cut or pressed, and F F', &c., a series of stars. Series A A', &c., B B', &c., D D', &c., and F F', &c., are parallel, the fans A A' forming one margin of the design and the stars the opposite margin. Points *b* of the figures B B', &c., extend between the fans. Points *d* of

the quarter cut or shaped figures extend into the fans, and the stars F F', &c., are each opposite the points *d*' of the figures D D', &c. 30

As shown, my design is applied to the margin of the dish—that is, as a marginal band; but it is obvious it might be embodied in a stripe as well as in a band. 35

I claim—

The design for ornamentation for glassware herein shown and described, the same consisting in a series of marginal fans A A', &c., 40 a series of ornamented diamond-shaped figures B B', &c., a series of diamond-shaped figures D D', &c., and a series of stars F F', the series being parallel, points *b* of figures B B', &c., extending between the fans A A', &c., the points *d* of figures D D', &c., extending 45 into the fans A A', &c., and the stars being opposite the points *d*' of figures D D', &c., the folds of each fan radiating from a common center *a* at the point *d* of a diamond-shaped figure A A', &c., and there being a 50 clear space between each star.

THOMAS SINGLETON, JR.
